UNITED STATES PATENT OFFICE

156,586

SPORT SHIRT

George E. Von Elm, Burbank, Calif., assignor to Palomino Sportswear Company, Los Angeles,
Calif., a corporation of California

Application December 16, 1947, Serial No. 143,169

Term of patent 14 years

(Cl. D3—25)

To all whom it may concern:

Be it known that I, George E. Von Elm, a citizen of the United States, residing at Burbank, in the county of Los Angeles and State of California, have invented a new, original, and ornamental Design for a Sport Shirt, of which the following is a specification, reference being had to the accompanying drawing, forming part thereof.

Figs. 1 and 2 are front and rear views, respectively, of a sport shirt, showing my new design.

I claim:

The ornamental design for a sport shirt, as shown.

GEORGE E. VON ELM.
